Primary Examiner—Wallace R. Burke*Assistant Examiner*—Joel Sincavage*Attorney, Agent, or Firm*—Larson and Taylor**[57]****CLAIM**

The ornamental design for an electrical switch actuator, as shown and described.

DESCRIPTION

FIG. 1 is a perspective view of an electrical switch actuator, showing my new design;

FIG. 2 is a front elevational view of FIG. 1;

FIG. 3 is a back elevational view of FIG. 1;

FIG. 4 is a right side elevational view of FIG. 2;

FIG. 5 is a top plan view of FIG. 1; and,

FIG. 6 is a bottom plan view of FIG. 1.

The side opposite to FIG. 4 is a mirror image thereof.

FIG. 1

FIG. 2

FIG. 3

FIG. 4

FIG. 5

FIG. 6
